UNITED STATES PATENT OFFICE.

GEORGE S. BARKENTIN, OF HARTFORD, ASSIGNOR TO P. & F. CORBIN, OF NEW BRITAIN, CONNECTICUT.

DESIGN FOR BIRD-CAGE HOOKS.

Specification forming part of Design No. **11,245**, dated June 17, 1879; application filed May 9, 1879.
[Term of patent 7 years.]

To all whom it may concern:

Be it known that I, GEORGE SLATER BARKENTIN, of the city of Hartford, in the county of Hartford and State of Connecticut, have originated and produced a new and original Design for Bird-Cage Hooks, of which the following is a full, clear, and exact description, reference being had to the accompanying sketch, making part of this specification.

The nature of my design consists in the general outline and ornamentation of the bird-cage hook, as shown in the drawing.

The architectural double lines A start from a flat circular base, B, and reunite at center C, terminating with a hook dropping at right angles from the main line of the stem. The ornamentation of said architectural lines consists of sunken panels, the ground of which

is composed of closely-traced vertical lines. At the center C the panel incloses a small ornamental spray, and in the open space formed by a division of the architectural lines is an ornamental scroll, D.

At the junction of the main architectural line and dropping hook, preferably springs upward and back toward the base B, a flowing Raphaelesque scroll, E, forming a partial support to an English pheasant, F, which holds in its beak a berry and leaves.

I claim as my invention—

The design for a bird-cage hook, substantially as shown and described.

GEORGE SLATER BARKENTIN.
